Calvin H. Brown

By Geo. A. Remington, Secy.

INVENTOR.

UNITED STATES PATENT OFFICE.

FRANK P. BARNEY, OF CHARTLEY, MASSACHUSETTS, ASSIGNOR OF ONE-HALF TO CHARLES D. LYONS, OF MANSFIELD, MASSACHUSETTS.

SEPARABLE CUFF LINK-BUTTON.

No. 885,135.

Specification of Letters Patent. Patented April 21, 1908.

Application filed July 25, 1907. Serial No. 385,405.

To all whom it may concern:

Be it known that I, FRANK P. BARNEY, a citizen of the United States of America, and a resident of Chartley, in the county of Bristol and State of Massachusetts, have invented certain new and useful Improvements in Separable Cuff Link-Buttons, of which the following is a specification.

My invention relates to cuff link-buttons and more particularly to separable buttons of such class, and it consists, essentially, of a pair of independent button-front or head members proper each having a flat shank or post and a flanged back head substantially rigid therewith, and a swinging spring-pressed rotatable central link or tongue mounted in one of said front heads and extending longitudinally through its shank and back head and being detachably connected in a yielding or flexible manner with the back head of the other button member, all as more fully hereinafter set forth and claimed.

The object I have in view is to produce a separable cuff link-button having each button head member thereof capable of being readily mounted and retained in the respective buttonholes of the cuff, and having said head members adapted to be quickly and easily connected and disconnected at will. The connecting medium or device also permitting the buttons to change their position with respect to each other in a direction longitudinally of the buttonholes of the cuff.

My improved cuff-button is strong, simple, comparatively inexpensive to manufacture, solderless, not liable to get out of order or become inoperative, flexible as before stated, and may be made in any style of design or ornamentation to which articles of this class are adapted. It may be added that the construction and arrangement of the members comprising my improved cuff-button are such that it may be readily inserted in the cuff and the parts connected or united, and as readily disconnected, by the user and even while the latter is wearing the garment, or shirt, and this, too, without the liability of dropping the parts or accidentally disconnecting and possibly losing them.

In the accompanying sheet of drawings, Figure 1 represents a plan or top view of my improved cuff-button normally mounted in a cuff, the ends of the latter only being indicated. Fig. 2 is a longitudinal central sectional view of the device in partial side eleva-

tion, the parts being in the normally locked position, and in enlarged scale. Fig. 3 is a corresponding plan view, partly in section, and also corresponding with Fig. 1. Fig. 4 is a transverse sectional view taken on line 60 4-4 of Fig. 3. Fig. 5 is a partial section, greatly enlarged, taken on line x-x of Fig. 2. Fig. 6 shows a front elevation of the back plate or disk of the button-head. Fig. 7 represents one of the blanks from which the shank or post is formed. Figs. 8, 9 and 10 represent views of a pair of said blanks when properly bent to form the shank, and Fig. 11 is a partial longitudinal section, corresponding with Fig. 2, showing a slight modification 70 in the form of the coupling link.

In my improved separable cuff-link-button A represented herewith and forming the subject of this invention B and B¹ designate the two main or front heads or buttons proper, D the shank members secured thereto, and r the tongue or coupling link, all made of suitable sheet metal stock. The shanks D of the two button members may be alike.

In the drawings I have represented the shank of the button B as differing slightly from that of the fellow button B¹. That is to say, in the former a pair of the blanks, as shown in Fig. 7, are bent and passed through the central slotted opening c¹ of the usual 80 back disk or plate c until arrested by the base part a of the shank; the shank portions proper, a¹, then lying flatwise upon each other, as shown in Figs. 2 and 3. The outer or free end of the shank terminates in an oval-shaped flange a² having an elongated central opening a³ extending parallel with and widthwise of the shank. Said flange is preferably covered with thin stock bent to a suitable convex form and constituting what 85 may be termed a guide or centralizing shoe s. See also Fig. 4. The shoe has an opening s¹ registering with said opening a³. The shoe fits rigidly to and under the ends a⁷ of the flange a², while at the same time permitting a slight lateral separation of the latter if desired. That is to say, the portions a¹ of the shank, assuming the stock to be somewhat resilient, is adapted to yield or open 90

upon pressing the spear-head end r³ of the link r (Fig. 11) endwise through the said opening a³, the sides springing together again after the parts are thus loosely locked together. The base end a of the shank of button B has a circular opening a⁴ cut there- 105 110

through, the adjacent ends a^5 of the stock (Figs. 8, 9) forming shoulders or stops adapted to prevent the head r^1 of the link, when the latter is turned axially about 90° from the normal or locked position, from dropping out, the central opening a^6 between the shoulders being large enough to freely permit said movement of the link.

The coupling member or link r is, as drawn, substantially square cross-sectionally, one end terminating in a cross-bar r^1 , thus forming a T, and having the opposite end r^2 provided with short lateral projections adapted in use to hook under the adjacent portions of said flange a^2 of the shank D, as clearly shown in Fig. 2. I prefer to make the two opposite sides of the bar r^1 slightly curved or beveled, and having a portion of the plate c correspondingly recessed, as indicated more clearly at c^3 in Figs. 5 and 6. A thin disk-like spring-plate d is also secured in the button members, the same being mounted so as to bear in a yielding manner at all times against the surfaces of the adjacent bases a and the bar r^1 .

From the foregoing description it is obvious that as drawn the link r must be rotated axially in order to lock and unlock it after its free end r^2 has been passed through the openings s^1 a^3 of the shank of the corresponding button member B^1 . To facilitate such movement of the link the latter is provided with a suitable fixed enlargement or arm, as l , adapted to be readily manipulated by the fingers of the user. Assuming now the button to be separated, the wearer first introduces the shoe and contiguous shank portions of the two main members, B, B^1 , through the respective buttonholes of the cuff's ends m , the projecting portion of the link r of the front button, B, obviously being inserted through the corresponding button-hole at the same time, the arm l then lying horizontally, i. e. in the dotted line position indicated in Fig. 1; the two parts of the cuff are then brought nearer together sidewise, the end r^2 of the link at the same time freely entering and passing through the openings s^1 a^3 of the shoe and shank, after which the link is turned 90° , at which instant the T-head r^1 thereof snaps into the recess c^3 , thereby hooking the said projections of the end r^2 under the flange a^2 of the shank of the corresponding button B^1 ; the position and relation of the parts then being substantially as represented in Figs. 1, 2 and 3.

It may be added that the length of the arm l or other analogous member of the link need not exceed the length of the buttonhole, and at the same time be quite small and light, since a comparatively slight pressure is sufficient to turn the link or coupling member from the locked to the unlocked position, and vice versa. My improved cuff-button is flexible, that is the link is adapted to swing in

either direction (see arrows, Fig. 3) within the limits of the openings s^1 a^3 while the button members B B^1 are locked or coupled together; conversely, the button members themselves are capable of movement in the buttonholes of the cuff, the latter itself being flexible and movable within fixed limits with respect to the button. The shank or post of each button is bifurcated and adapted to spring apart laterally to permit the entrance of the link's enlarged free end, and especially if the latter be made spear-shaped, as indicated at r^3 , Fig. 11. It is clear that the two main parts of the button cannot become disconnected unless the link be first turned axially about 90° , thereby placing the widest part of the end, r^2 or r^3 , in alignment with the longitudinal axis of the shank opening a^3 . Of course the same result may be attained by simply turning one or the other of the button members B B^1 90° , but this action is obviously impracticable when they are mounted in the buttonholes of the starched cuff.

I claim as my invention and desire to secure by United States Letters Patent:—

1. As an improved article of manufacture a separable cuff-link button, the same comprising a pair of independent button members each provided with a fixed shank terminating in a lateral flange or enlargement adapted to pass through a buttonhole of the cuff and retain said member therein, a swinging coupling member or link mounted in one of the button members and extending longitudinally beyond its flange, and having the free end of said link constructed to engage with the fellow-button member for detachably securing them together.

2. In an article of the character described, the combination of a pair of main button members, each having a bifurcated laterally yielding shank terminating in a suitably capped and apertured flange, a spring-pressed tongue or link revolvably mounted in one of said buttons and extending outwardly therefrom through its shank, and having the free end of the link enlarged and adapted to pass freely through the flange of the shank of the other button and hook thereunder, substantially as described.

3. In an article of the character described, the combination with a pair of oppositely disposed main button members, each provided with a fixed comparatively short shank or post terminating in a centrally apertured flanged part, of a spring-pressed connecting link or tongue movably mounted and supported in one of said button members and projecting outwardly beyond its shank and interlocking with the shank of the other button member, and an arm or analogous device secured to the link whereby the latter may be manipulated axially for detachably connecting the two buttons together.

4. In an article of the character described,

the combination with the buttons B B¹ having flat resilient shanks provided with apertured capped ends, of a spring-pressed rotatable link mounted in one of said buttons and extending through its shank and arranged to be detachably connected with the shank of the other button, means for holding the link in the normally locked position, and having the opening in said shanks elongated in the plane of its width, corresponding when in use

with the plane of the buttonholes of the cuff, whereby the link is adapted to swing a limited distance therein, substantially as described and for the purpose set forth.

Signed at Providence, R. I., this 23d day 15 of July, 1907.

FRANK P. BARNEY.
